W. P. HENRY

BOTTLE CLOSURE

Filed June 12, 1926

William P. Henry INVENTOR

BY J. S. Newton
ATTORNEY

UNITED STATES PATENT OFFICE.

WILLIAM P. HENRY, OF NEW YORK, N. Y.

BOTTLE CLOSURE.

Application filed June 12, 1926. Serial No. 115,591.

My invention relates to a closure for the filling and discharging opening of a vessel or container, but more particularly a closure for the opening of milk and cream bottles in connection with which certain particular requirements are desirable and important and sometimes essential.

More specifically the objects of my invention include the provision of a closure for milk bottles that will be economical to make, serviceable in every respect, and above all economically applied for their proper functioning. As to the application, my invention involves a closure which may be either hand applied where the volume of bottling business does not warrant the installation of expensive machine equipment for affixing the closures, or where machine equipment of the simplest existing form exists, in which latter case my closure permits of more economical capping of bottles than heretofore has been the case where sanitary protection of the bottle lip is desired.

With these characteristics and objects, which will more particularly appear from the following specification, particular embodiments of my invention are shown in the accompanying drawings, in which:

Fig. I is a vertical section of the top or neck of a milk bottle with a form of my closure affixed.

Fig. II is half of a vertical section of a milk bottle rim with a cooperating attaching plug or mandrel, approximately double full size.

Fig. III is a cross-section of half of a closure as manufactured before attachment to a bottle neck.

Fig. IV is a modified form of closure as manufactured, in cross-section.

Fig. V is a cross-section of another modified form.

Fig. VI is a cross-section of another modified form of closure.

Fig. VII is a perspective bottom view of a closure.

Fig. VIII is a perspective view of the top side of a closure.

Fig. IX is a perspective view of a disc or cap portion, separated for illustration.

As shown, the disc, usually called the cap 1, is of stiff pasteboard covered with paraffine to make it impervious to the milk or other contents of the bottle and for sanitary purposes. Above this cap is a cover 2 which

is consolidated with the cap 1, in various ways. This cover comprises a portion 3, which is a flat disc-shaped member of material preferably not as stiff as the material of the cap and extending almost to the edge 60 of the cap 1, but leaving a small clearance, as shown in Fig. III. Another portion of the cover extends laterally at 4 and forms a skirt 5 fitting the outer surface of the bead, that is the upper portion of the top of the 65 bottle, which preferably terminates at 6 in an attenuated or even ragged edge adapted to cling to the smooth surface of the glass of the bottle.

As shown in Fig. I, the cap is glued 70 throughout the major portion of their juxtaposed surfaces, while in the form shown in Figs. VII and VIII there is a plurality of thin wire staples 8 punched into the upper surface of the cover layer of paper or other 75 material, and clinched as shown at 8', preferably into the material of the cap 1. These prongs on or adjacent the inside surface of the cap 1 may be covered with paraffine, but in any event they are punched from the outer 80 or top side, or in such manner as to absolutely preclude the chance of their becoming detached and falling into the milk, and they are so fashioned and applied as to prevent any interference with the hermetic sealing 85 of the device.

In Fig. IV the cap 1 has the closure 2 attached by the staples 8, but one of the staples 8^a is preferably larger and stronger in order that it may hold the adjacent material of the flat portion 3 of the cover so that a flap 9, cut out of the material of the cover portion 3, is provided as a finger hold or grip which may be easily raised by the finger nail and give a sufficient hold to raise the 95 entire closure out of the neck of the bottle from its locked position. It may also be provided that such removing flap tears the cover A away from the disc 1 by dislodging the staple 8^a, by making the other staple 100 stronger, so that the first act of attempting to remove the closure constitutes an act of violating the integrity of the structure, and thereafter the more firm connection by the other staples permits pulling out the cap, 105 whereby the operation of removal first causes an irreparable tearing of the structure, and thereafter the connections provide readily for facile decapping or opening of the bottle. In Fig. V a staple or clinch 8^b 110

is shown, which connects the cover portion 3 with the disc or cap 1, and which simultaneously and firmly connects a removing tab 9^a, of tough paper or other suitable material so securely held that the pull thereon will dislodge the entire closure from the bottle neck. In Fig. VI is shown a connection between the cover and the locking disc 1 comprises a relatively large staple 8^c, and 10 one or more smaller staples 8^d, which aim to provide for a complete central portion 3 of the cover 2, in a manner whereby the staple 8^d will tear away from the disc 1 when the bead 5 of the cover is ripped or 15 pulled away, and thereby mutilate the complete unit structure, but which still leaves a firm union due to the more robust clinch of the staple 8^c which thereupon serves to pull out the cap 1 which is the real stopper, by 20 means of the entire cover as a handle of more convenient and ample size for manipulation.

It will be seen from Fig. II that an attaching plug or mandrel 10 is readily provided with a pressing or battering top 11, and a closure set-rib 12 which is of an exact size necessary to press the cover portion 3 near its recessed rim, and thereby transmit the pressure near the periphery of the cap 30 1 in order to drive the rim of the stopper-cap to the seat or shoulder 13 formed in the glass of the neck of the bottle. Likewise this rim 12 of the plunger or mandrel will be guided by the formation at 14, so that 35 the edge of the setting-rib 12 will be always concentric and thereby drive the closure, top and cap, close to its rim, to a firm seat on the step 13. Such a mandrel will, furthermore, conform at the surface 15 with 40 the standard section of the lip surface of the bead of the bottle, with only such tolerance or allowance necessary to accommodate the thickness of the skirt where it fits the outer surface of the bead, and to accommodate the lateral portion of the cover at 45 4 where the process of manufacture in stamping the cover may accumulate a slight excess of thickness of paper or pulp. It will here be seen that Fig. II, in conjunction 50 with Fig. III, illustrate in more detail important requirements for producing the most successful form of my closure, for most economical production as well as for the assurance of more uniformly secure attachment. 55 In particular this is realized by having the cap 1 of the necessary thickness, such as approximately four to five hundredths of an inch, with stiff paper suitably paraffined and of a texture that assures the lip 1^a 60 adapting itself to a crimp shown at 1^b, in order to form a locking engagement with the wall 16 in the neck of the bottle above the seat 13, which wall 16 is practically cylindrical, or slightly varies in diameter if 65 glass manufacturing operations permit, as,

for instance, very slight bulging in cases of the minimum diameter at the extreme top of the wall neck. With such a disc the cover portion being formed of hard or tough paper, and in no case fragile, the union of 70 the portion 3 of the cover with the top surface of the cap 1 provides a stout bulk of material of a minimum thickness, so that the pressure on the mandrel 10 causes the edge 75 rim 12 to force the periphery of the portion 3 of the cover into the neck, and with the rim guided concentrically it transmits the pressure to the cap or stopper-disc 1 on a circle close to the rim so as to force the disc to its seat 13 and permit the small annular portion 1^a to bend or crimp in order that it may 80 slide into the bottle neck along the wall 16 simultaneous with a slight deformation in the nature of buckling, which leaves the stopper-disc 1 seated firmly and sealing the bottle 85 by contact with the step 13, with its periphery in engagement with the wall 16 in a manner that resists extraction against any normal pressure of the contents of the bottle. The advantage will thus be realized in 90 having the contact of the cover portion 3 at its periphery 3^a, immediately adjacent the edge of the stopper-disc 1, in order that the closing or sealing pressure by a mandrel, or even by the finger, will force the disc near 95 its edge, and not at its middle, into the locking position, in order that the stopper-disc may properly reach its seat and that the slight excess of material due to its size, will be deformed at its rim for the purpose of 100 the locking engagement. The importance of this will be realized when it is considered that in the formation of glass bottles, suitable for milk, cream, buttermilk and the like, the neck is most readily formed substantially cylindrical from the extremity inward along the wall 16, and to the seat 13. Even though any recess might be formed, it would be inviting unsanitary accumulations or defeat the purpose of simplicity in cleaning 105 for reuse.

In the case of hand closing and where no mandrel or plug is used, I may form the lateral walls 4^a of the cover 2 as shown in Figs. IV and V, namely, with a sharper bend 115 at 3^a and a straight wall only slightly diverging to the top 4 of the bead, and preferably made of stiffer material than when intended for machine application. By this formation I provide a short, stiff, almost 120 cylindrical portion of the cover serving to transmit pressure from the top of the bead 4 directly to the disc close to its edge but inside of the rim 1^a. The material can be such, and the cover made and attached to the disc in a way admirably suited to insure pressure on the cover forcing the locking disc or stopper 1 to its seat all around, while at the same time forcing the rim of the cover snugly on to the bead of the bottle top. 125 130

In the form shown in Fig. IV it will, furthermore, be noted that forming the flap 9 removes part of the material of the flat portion 3 of the cover, and depending upon the size of the flap or "pull" more or less of the material may be so used and where desired a large portion of the area 3 of the material as an annular rim is left to provide a firm attachment between the bottom of the cover and the top surface of disc 1 a little back of its periphery, so as to leave the seal-crimpable edge 1^a. In certain forms I prefer to omit the flap, and when so made the cover portion comprises the bead fitting skirt with the wall 4^a and a small annular rim which is securely fastened, preferably glued, on to the top surface of the disc A. In this latter form the paper or other material used, that is cut out of the area 3, is saved in the ultimate product, and while it might then be scrapped, it might also constitute discs that could be of the exact size for use on other product. In fact, as there is a variation or at present there are at least two sizes of diameter in general use for the sealing caps of bottles, in case it is found desirable to use the same quality of material in the cover, then the disc cut out of the portion 3 might serve for use as the closing disc or stopper in smaller sizes of closures containing my invention.

The closure thus serves most admirably the securing in the normal and preferable design of bottle necks both as to security of closure, and also with reference to the attachment and in addition the simultaneous attachment of the cover to conform to the lip of the bottle orifice. The lip of the bottle is preferably formed with a slight curvature over which the cover portion 4 fits, substantially horizontal and downwardly curved where the portion 5 of the cover fits to a point 17 where the usual manufacture of bottles leaves a slight but varying flash or excrescence in the glass. This flash 17 may be in the horizontal plane of the step 18, but may vary depending upon the process of manufacture of the bottles, and in any event it provides a slight ridge which may be almost as much as the thickness of the required paper material used in the cover, namely, in the order of .025 to .003" in thickness. Thus the cover edge 6 may readily be made for standardization in its adaptation to standard bottles, so that the flash on ridge 17 protects the edge 6 of the cover, and in this manner the ridge forms a guard to prevent accidental pulling of the cover edge 6 to minimize the chance of accidental dislodgment of the entire closure. At the same time this cover in no way interferes with the ordinary handling of the bottle by gripping the reentrant outside curved surface 18 of the bead below the top of the bottle, which normally forms

the convenient grip for the milkmen, and others, in the handling of milk, cream, and other bottles of this character.

It will thus be seen that my closure provides a complete unit which can be manufactured and delivered to the bottler ready for attachment either by hand or by machine to the top of a bottle. It provides a closure that can be manufactured of stiff material and which may be sized on the cover if desired, for the purpose of clear printing which is usual in milk bottle stoppers, and being a unit the printing of the bottler's name, the day of bottling or the time of bottling may be printed on the outside cover and not on the inner disc which forms the actual closure, but still consolidating the inside closure with the cover in such a way that the identity of the bottling is inviolate so far as any difference between the closure disc or cover is concerned. Both closure and cover are one, with the paraffine contents protection assured by the inside surface which also locks in the bottle, while the outside cover can be of the material best suited for handling and printing and to suitably cling to the lip of the bottle and protect it under all of the normal and ordinary conditions. It provides also that the disc may be made of the best material suitable for its function, while the cover material may be made of different material best suited to avoid the collection or retention of dust and dirt, and amply tough for the ordinary pulling operation and for the handling of the stoppered bottles, while the particular structure provides for the driving home of the unit into the neck of the bottle in a manner that assures a proper sealing of the disc without the chance of rupturing any of the paper or other material used in the operation, no matter how hard a pressure may be required to properly seat the disc on the inside.

While many variations may be made in details of design or changes in material, from my preferred forms herein described in detail, without departing from the spirit of my invention,

What I claim and desire to secure by Letters Patent is:

1. An article of manufacture consisting of a unit comprising a bottle lip protector adapted to be held to the bottle top by a sealing cap and having the two elements of a disc of stiff paper or like material paraffined or similarly treated on the bottom and adapted in size and stiffness to be inserted into the neck of a bottle by pressure and to resist ejection due to internal pressure, a second part secured around said disc near but slightly away from the periphery and having a rising wall extending to the lip of a bottle and a continuous formation of material laterally

- outward and downward over the lip and 5 outward and downward over the lip and the immediately adjacent outer surface of the bead of a bottle and having its outer rim of a diameter slightly less than the maximum diameter of the outer surface of the bottle bead whereby upon pressing the disc into sealing position the outer rim of the cover moves to a sealing contact with the outer surface of the bottle bead above the line of its maximum diameter.
2. An article of the character described having its hood formed from the union with the disc in a truncated cone with straight walls adapted to transmit pressure on the top of the cover to the disc in an annular area near its rim and against the disc-engaging ledge in the neck of the bottle, and having the outer depending rim of the hood of a diameter slightly less than the maximum diameter of the outside of the bottle bead to engage and form a seal against the outer surface of the bottle bead above its line of maximum diameter when the disc is forced to its sealing seat.
3. A bottle stopper comprising a locking disk adapted to resist the internal pressure of the content liquid of the bottle, a cover consolidated with said disk, a union between the cover and the disk permitting pressure in a circle so close to the periphery of the disk for its application that the disk and cover are forced to the seating position without rupture of the cover material and contiguous extension of the cover over the lip of the bottle and terminating with its lower edge in forced contact with the outer surface of the bottle lip above its maximum diameter to prevent ingress of moisture or impurities over the bottle lip from the outside.
4. In testimony whereof, I have signed my name to this application this 11th day of June, 1926.

WILLIAM P. HENRY.
